A. G. F. KUROWSKI.
TYPE WRITING MACHINE.
APPLICATION FILED JAN. 14, 1913.

1,190,658.

Patented July 11, 1916.

UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,190,658.

Specification of Letters Patent. Patented July 11, 1916.

Application filed January 14, 1913. Serial No. 741,911.

To all whom it may concern:

Be it known that I, ALFRED G. F. KUROWSKI, a citizen of the United States, residing in Brooklyn, in the county of Kings, city 5 and State of New York, have invented certain new and useful Improvements in Type-Writing Machines, of which the following is a specification.

This invention relates to line-spacing 10 mechanism of typewriting machines, particularly those employing revoluble platens.

The principal object of the invention is to provide improved and simplified means 15 easily applicable to existing machines and cheaply manufactured, for preventing the platen from being driven at excessive speed, and to protect the platen and line-spacing mechanism from the objectionable effects of sudden and violent operations of the usual 20 line-space lever or handle which is used on the Underwood or other machines for both rotating the platen and returning the carriage to begin a new line of writing. Excessive speed or violent or jerky operation 25 of the line-spacing mechanism is objectionable because it results in wear and tear of the mechanism; the platen is apt to start ahead of the work-sheet thereon and thereby make the line-spacing uneven; and is 30 also apt when being driven at high speed and suddenly arrested to effect further dis-arrangement of the work-sheet or work-sheets.

According to my present improvements, a 35 yielding connection is provided between the line-spacing handle and the lever which drives the line-spacing pawl. The handle is preferably placed upon a slide which is mounted to be driven along the typewriter 40 carriage; and said slide is preferably connected by a coiled spring to the forward end of the line-space lever. The speed of operation of the platen depends not upon the speed of operation of the handle, when the 45 latter is rapidly operated, but upon the strength of the spring; and hence the platen can never turn any faster than the spring will drive it. Stops are provided for limiting the stroke of the handle and slide; and the usual adjustable devices are provided for the line-spacing pawl, for regulating the line-spacing movement of the platen.

Other features and advantages will hereinafter appear.

In the accompanying drawings, Figure 1 55 is a perspective view of an Underwood platen and its appurtenances, showing my present improvements applied thereto. Fig. 2 is a cross section illustrating the line-space wheel and pawl. Fig. 3 is a front elevation 60 of the line-space handle and its slide. Fig. 4 is a plan of parts seen at Fig. 3.

In the usual Underwood type of machine to which my invention is shown applied, the platen 1 is fixed on an axle 2 journaled in 65 the ends 3 (only one of which is shown) of a platen frame 4 supported on a carriage 5. The platen 1 is rotated by means of a bell crank 6, the arm 7 of which engages and drives rearwardly a slide 8, carrying a pawl 9 to engage a ratchet wheel 10 fixed to the platen axle 2. A stop 11 is formed on the platen frame 4 to arrest the pawl 9 after turning of the platen. If the pawl were driven back against the stop 11 too violently, the stop would become battered and hence the pawl would be liable to travel too far, producing thereby a faulty action of the line-space mechanism. Furthermore, when the platen is started rapidly into rotation, it gets started in advance of the work-sheet held frictionally against the surface of the said platen, by means of the feed rolls 13. To avoid these difficulties, I have devised improved means, whereby only the 85 required amount of power can be applied to the line-spacing mechanism.

Mounted slidably upon the front of the carriage 5 is an operating member for the line-space lever, said member shown as a 90 bar 14, having a horn or handle 15 by means of which said bar may be moved. A spring 16 attached at one end to the bar 14 connects the same to the bell crank 6, to cause the latter to turn the platen. When the 95 handle 15 is struck sharply it will distend the spring 16 until the ends of the slots 17 reach the studs 18, the pressure thus transmitted to the carriage causing it to travel in its return movement toward the right. 100 In the meantime, the spring 16 will force the pawl 9 to rotate the platen 1.

The regulation of the line-spacing of the platen is effected by setting a shiftable slide 19, having a ledge 20 upon which the pawl 105 9 rides, in a position which permits said pawl 9 to ride off the ledge sooner or later to engage and adjust the ratchet attached

to the platen. This slide is held by a spring 21, and is controlled by a lever 22 extending above the platen frame 4.

Variations may be resorted to within the scope of the invention, and portions of the improvements may be used without others.

Having thus described my invention, I claim:

1. In a typewriter, the combination of a line-spacing mechanism comprising a line-space lever, a pawl operated thereby to rotate the platen, feed rolls bearing upon said platen and receiving motion therefrom, a member operable to return the carriage, and elastic means between said member and said line-space lever to transmit the required power to the latter to actuate the line-spacing mechanism.
2. In a typewriter, the combination of a line-spacing mechanism comprising a line-space lever, a pawl operated thereby to rotate the platen, feed rolls bearing upon said platen and receiving motion therefrom, a member to operate said line-space lever, and means to limit the amount of power transmissible from said member to the line-space lever to prevent the platen being started to rotate too rapidly and cause a slip between the platen and the feed rolls.
3. In a typewriter, the combination with a line-spacing mechanism comprising a lever and a pawl operated thereby to rotate the platen, of an operating member, and a spring connecting said member to said line-space lever, said member capable of distending said spring sufficiently to actuate the line-space mechanism.
4. In a typewriter, the combination of a

line-spacing mechanism comprising a line-space lever, a pawl operated thereby to rotate the platen, a stop to limit the amount of travel of said pawl, an operating member, and means forming a driving connection from said member to said line-space lever and operable to limit the amount of power transmitted to the latter to prevent the pawl striking the stop with undue force.

5. In a typewriting machine, the combination with a traveling carriage and a rotatable platen thereon, of a line-spacing mechanism for rotating the platen, a slide on the carriage having a limited movement relative thereto, and elastic means connecting the slide with the line-spacing mechanism and operating to prevent excessive force being applied to said mechanism.

6. The combination, in a typewriting machine, of a traveling carriage and a rotary platen thereon, line-spacing mechanism comprising a line-space lever and a pawl, a slide on the carriage having a limited movement relative thereto in the direction of the carriage travel, and a coil spring connecting said slide and said line-space lever.

7. The combination, in a typewriting machine, of a traveling carriage, a rotary platen, line-space mechanism, a manual device for returning the carriage and operating said mechanism, and a tension spring extending in the direction of the carriage travel and forming a connection between said device and said line-space mechanism.

ALFRED G. F. KUROWSKI.
